UNITED STATES PATENT OFFICE.

WILLIAM MCNAMES, OF ABERDEEN, SOUTH DAKOTA.

DOWNSHILL CHECK FOR VEHICLES.

Application filed May 9, 1921. Serial No. 467,980.

To all whom it may concern:

Be it known that I, WILLIAM MCNAMES, a citizen of the United States, residing at Aberdeen, in the county of Brown and State of South Dakota, have invented certain new and useful Improvements in Downhill Checks for Vehicles; and I do declare the following to be a full, clear, and exact description of the invention, such as will enable others skilled in the art to which it appertains to make and use the same.

This invention relates to an improved device which is designed for checking forward movements of vehicles on inclines in case the engine accidentally stops or for any other reason necessitating stoppage of the vehicle on a down-grade.

The principal object of the invention is to generally improve upon devices of this class by providing one of extreme simplicity and durability which will effectively accomplish the desired results and yet not raise the rear end of the vehicle off of the ground as do many other similar devices of this class.

Another object of the invention is to provide a device of this class which is composed of comparatively few strong and durable parts which are such that they can be connected to the vehicle by inexperienced persons.

Other objects and advantages of the invention will be apparent during the course of the following description.

In the accompanying drawings forming a part of this specification and in which like numerals are employed to designate like parts throughout the same:

Figure 1 is a side elevational view, with parts shown in section, of a device constructed in accordance with this invention showing the same in operative position on a vehicle chassis.

Figure 2 is a similar view showing the device in inoperative position.

Figure 3 is a rear end elevation with the ground engaging shoe in section.

Figure 4 is a top plan view showing the manner of connecting the device to the chassis.

Figure 5 is a detail perspective view of the shoe.

Figure 6 is a perspective view of a detail of the attaching means.

Figure 7 is a transverse section taken substantially on the plane of the line 7-7 of Fig. 1.

Before proceeding with the detailed description of the invention, I wish to point out that I have disclosed many parts which are substantial duplicates of the corresponding parts disclosed in my co-pending application Serial No. 467,979, filed May 9, 1921, for an improved anti-skid device for automobiles. These parts that I have reference to are specifically described in the above named application and constitute no part of this invention. Therefore, they need be only referred to briefly. To this end, 1 designates an attaching plate disposed on the rear axle housing H and clamped thereon by any suitable means, such for instance by the U-bolts 2. Here, I may point out that this attaching plate has associated with it, like the one shown and described in the aforesaid application, novel anchoring means 3 for preventing possible slippage and rotation thereof on the axle housing, this means co-acting with the spring as shown. Extending crosswise of the attaching plate 1 and beyond the longitudinal edges of the latter is a second plate 4 provided at its forward end with a guide 5 for passage of the operating cable 6. The rearwardly extending and depending portion 7 of this plate 4 instead of being solid like the corresponding parts shown in my co-pending case above named, is bifurcated near its lower end as indicated at 8 forming a pair of arms 9, the lower ends of which are bent upon themselves to form bearings 10 for the journaling of a pivot pin 11 which serves as a mounting means for an extensible leg 12 which is connected thereto intermediate its ends as shown.

The parts above referred to with the exception of the leg 12 are substantial duplicates of the corresponding parts shown and specifically described in my co-pending case already named, it being understood that the plate 4 is bifurcated at 8 to accommodate the particular kind of leg herein shown. It may be stated that the leg could well be of the same construction as the one shown in the application under consideration. However, I prefer to vary the construction thereof and construct the same so as to include a tubular upper section 13, and a cylindrical plunger or lower section 14 which is slidable in the hollow portion of said upper section. The upper end of the section last named is designed to be received between a pair of jaws 15 carried by the depending

portion 7 of the plate 4. It is to be noted that these jaws are so constructed and the upper end of this sectional leg is likewise so constructed that when it is received between said jaws, it is held against undue and undesirable movement by friction. Referring now to the lower end of this tubular section 13, it will be seen that it is provided at diametrically opposite points with 10 guide-slots 16 in which the lateral extensions 17, carried by the cylindrical section 14 have limited sliding movement. Arranged within the socket or hollow portion of the section 13 is a coiled spring 18 which 15 bears against the upper end of the part 14 and serves to force the latter downward for a purpose to be herein described.

The invention in addition to embodying the aforesaid parts includes a pivotally 20 mounted ground-engaging shoe 19 which in its preferred form is equipped on its upper face with spaced ears 20 between which a cross-head 21 on the lower end of the leg section 14 is received and pivotally connected at 22. Attention is directed to the fact that the cross-head 21 is reduced in width toward its opposite ends so as to permit 25 pivotal movement of the shoe yet limit such movement so that it will not assume an undesirable position. It may also be mentioned that opposite ends of the shoe are 30 upturned as indicated at 23 to prevent these ends from digging into the surface and hanging, and not permitting effective operation of the device. The only other part of 35 the invention not yet described is a brace 24 secured to the plate 4 and including spaced arms 25 straddling the upper end of the leg section 13 and having their lower 40 ends engaged with the bearings 10 to reinforce and increase the rigidity of the depending portion 7 of this plate.

In operation, the leg is normally suspended in the inoperative position disclosed in 45 Fig. 2, being held in such position by means of the cable 6 which extends forwardly through the guide 5 and to a convenient point on the vehicle for operation by the driver or other occupant. By releasing the 50 cable 6, the leg 12 and foot 19 will drop by gravity and the foot will engage the ground being held in yielding contact with the latter by means of the spring which exerts a downward pressure on the leg section 14. When the shoe thus contacts the

ground, it will act like a brake and serve to bring the vehicle to a standstill. It is obvious that when the upper portion of the leg section 13 swings between the jaws 15, the rearward swinging movement of the leg 60 will be limited.

A careful consideration of the foregoing description taken in connection with the accompanying drawings is thought sufficient to enable persons skilled in the art to which the invention relates to obtain a clear understanding of the same. Therefore, a more lengthy description is deemed unnecessary.

Advantageous and effective results are practically insured with the construction 70 and arrangement herein shown and described. However, slight minor changes coming within the scope of the subjoined claims may be resorted to.

I claim:

1. A device of the class described comprising attaching means including a plate adapted for crosswise disposition on and connection to the rear axle of a vehicle, a leg pivoted intermediate its ends on said plate, spaced jaws on said plate between which the upper end of said leg is received and frictionally gripped when in operative position, and a ground-engaging element on the lower end of said leg.

2. A device of the class described comprising attaching means for connection to a part of the vehicle, a slotted tubular leg-section pivotally connected to said means, a spring-pressed section telescoping into 90 said tubular section and equipped with pins projecting slidably through said slots, a head on the lower end of said second-named section, and a surface-engaging shoe pivotally connected with said head.

3. A device of the class described comprising a plate for crosswise disposition on and connection to the rear axle of an automobile, including a depending rearwardly extending bifurcated portion, a leg pivoted 100 to and movable between the furcations of said plate, a brace carried by the latter including spaced arms between which the upper end of said leg is disposed when in operative position, and a ground-engaging 105 element on the lower end of said arms.

In testimony whereof I have hereunto set my hand.

WILLIAM McNAMES.
